(57) **CLAIM**

The ornamental design for a windshield for motor vehicles as shown and described.

DESCRIPTION

FIG. 1 is a front perspective view of a windshield for motor vehicles;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof;

FIG. 8 is a front view of the windshield engaged on a motor vehicle; and,

FIG. 9 is a side perspective view of the windshield engaged on a motor vehicle.

The broken line illustrations in FIGS. 1-7 form no part of the claimed design. The broken lines in FIGS. 8-9 illustrate the environment in which the design is embodied and form no part of the claimed design.
